APPARATUS FOR CONDUCTING SWEETENING OPERATIONS

Stanley Arthurs, Solon, Ohio, assignor to The Standard Oil Company, Cleveland, Ohio, a corporation of Ohio

Application April 8, 1953, Serial No. 347,450

5 Claims. (Cl. 196—46)

This invention relates to an apparatus for conducting sweetening operations on gasoline, naphthas, heating oils, kerosene, and the like.

The presence of elemental and combined sulphur in petroleum introduces special problems into the refining of the lower-boiling fractions, such as the gasolines and kerosene. The sulphur in the higher-boiling petroleum fractions, except for traces of hydrogen sulfide, is generally in the form of stable and neutral organic compounds, which have no deleterious effect on the oil; and generally no effort is made to remove them. The lower-boiling fractions, such as gasoline, occasionally contain elemental sulphur in small proportions, which must be removed by special procedures. Hydrogen sulfide is nearly always present and is removed by any simple method of washing the hydrocarbons with an aqueous alkaline reagent, such as caustic soda and the like.

Cracked naphthas nearly always contain small quantities of mercaptans which have an objectionable odor and other undesirable properties. The mercaptans are reactive chemically; they are acidic and are easily oxidized. Sometimes they are extracted from the oil quantitatively, but usually a portion of them is removed by caustic soda solution; the remainder is commonly transformed by a special oxidation procedure, "sweetening," into the less odorous alkyl disulfides which remain dissolved in the oil.

Cupric chloride is now in extensive use to oxidize the mercaptans of light oils to disulfides and thus sweeten the oils. The copper salt is reduced during the sweetening operation to the cuprous salt, but is re-oxidized by air at normal temperatures, the regeneration being simultaneous with the conversion of the mercaptans, if dry or solid copper salt is used, or by a separate operation if an aqueous solution of the copper salt is used. Some petroleum refiners use both the solid and liquid processes.

Hydrogen sulfide is conventionally removed from sour naphtha by an alkaline wash before copper sweetening, because copper sulfide which would form therefrom cannot be regenerated to an active sweetening agent by atmospheric oxidation.

In accordance with the present invention, a single unit of apparatus is provided for conducting sweetening operations and more particularly, those operations known as copper sweetening.

Among the advantages resulting from the use of the apparatus of the invention are savings in space requirements, reduced piping costs, reduced steel requirements for vessels and simplification of operation.

The invention will be further illustrated by reference to the accompanying drawings in which:

Figure 1 is a sectional view in elevation of one embodiment of the apparatus of the invention;

Figure 2 is a sectional view taken on line 2—2 of Figure 1.

The drawings show a typical installation for treating 7,500 barrels per stream day of sour kerosene, but any other low-boiling hydrocarbon may be treated in a similar manner.

2

The apparatus as illustrated is composed of a vessel that is divided across its vertical length into three compartments; a prewash compartment 20, a separatory compartment 10 and a treating compartment 54. The separatory compartment 10 is in turn divided into three sections as illustrated in Figure 2; i. e., a coalescing section 12, a coalescing section 14 and a washing section 16. Each of the coalescing sections is packed with a coalescing material 15 which is capable of removing water from hydrocarbons. The prewash compartment is provided with an inlet pipe 24 and an outlet pipe 26, the outlet pipe 26 being connected to pump 28 and to caustic regenerator 30 and rejoining mixing valve 56. The interior of the prewash compartment is provided with an outlet pipe 22 having an opening near the top of the prewash compartment 20 which leads to coalescing section 14. The coalescing section 14 is provided with outlet pipes 40 and 32, the latter of these pipes leading to heater 34, pump 36, eductor 8 and thence through pipe 38 into the treating compartment 54. Outlet pipe 40 leads to waste. The bottom of the treating compartment 54 is conically shaped and is provided with outlet pipe 6 which is also connected to eductor 8. The discharge side of pump 36 is provided with a means 39 for admitting cupric chloride and clay to the system. Connected to the inlet side of pump 36 is pipe 62 which serves the purpose of admitting oxygen or an oxygen-containing gas such as air into the system.

The treating compartment 54 is also fitted with a discharge pipe 42 which leads to mixing valve 64 and to pipe 48 and thence to washing section 16 of the settling compartment 10. Connected to the bottom of the washing section 16 is an outlet pipe 44 and a pump 46 the discharge side of which is connected to line 42 just prior to the mixing valve 64. The washing section 16 is also provided with an opening or orifice 18 leading into the upper part of coalescing section 12. Coalescing section 12 in turn is provided with two outlet pipes, an upper outlet pipe 50 and a lower outlet pipe 52.

The operation of the apparatus is as follows:

The prewash compartment 20 is filled initially with aqueous caustic solution. The sour hydrocarbon, which may be kerosene or another low-boiling fraction, is charged continuously to the system through mixing valve 56 wherein it is mixed with recycled aqueous caustic solution and the resulting mixture is then injected via pipe 24 into the prewash compartment 20 for the purpose of washing the hydrocarbon and removing any hydrogen sulfide which may be present in the feed. The caustic solution having a higher density than the hydrocarbon settles to the bottom of the prewash compartment and is recirculated through pipe 26 by pump 28 through caustic regenerator 30. From the caustic regenerator the caustic solution is returned to mixing valve 56. Instead of employing the regenerator, fresh caustic may be used, if desired, and the spent caustic sent to waste.

The prewashed hydrocarbon rises to the top of the prewash compartment and flows into an outlet pipe 22 and thence into the coalescing section 14. (The coalescing sections are packed with glass wool or a similar material 15 which is capable of removing aqueous components which may be carried into the coalescing section with the hydrocarbon.) The coalesced water (or aqueous caustic) settles to the bottom of coalescing section 14 and is discharged from the system through pipe 40.

The prewashed hydrocarbon is withdrawn from coalescing section 14 through pipe 32, passed through a heater 34 to insure complete solution of small amounts of water which may be retained by the hydrocarbon, and is then pumped by means of pump 36 through the eductor 8 and pipe 38 into the treating compartment 54. The treating chemicals, e. g., cupric chloride and clay, are

added as necessary to the discharge line of the pump 36 through pipe 39.

The treating chemicals that are present in treating compartment 54 settle into the conically shaped bottom of the treating compartment and are removed through pipe 6 via eductor 8 and are then returned through line 38 to the treating compartment 54. In this operation the treating chemicals react with the mercaptan sulphur present in the hydrocarbon and thus sweeten the hydrocarbons. Continuously with this operation, oxygen or an oxygen-containing gas is admitted to the system through line 62. The oxygen or oxygen-containing gas thus admitted is admixed with the hydrocarbon and chemicals which enter the treating compartment 54 and the treating agents are constantly regenerated by reaction with oxygen.

The sweetened hydrocarbon is withdrawn continuously from the top of the treating compartment 54 through pipe 42, mixed with a stream of circulating water withdrawn from the washing section 16 by pump 46, and the mixture of water and hydrocarbon is pumped through line 48 into the washing section 16 wherein the last traces of treating chemicals are removed from the hydrocarbon.

Within the washing section 16 the water settles and is recirculated through line 44 while the hydrocarbon rises to the top of the washing section and flows through the opening or orifice 18 into the second coalescing section 12. Within the coalescing section 12, which is also packed with glass wool or a similar material 15, any water which is carried over in the hydrocarbon from the washing section is removed from the hydrocarbon, settles to the bottom of coalescing section 12 and is discharged therefrom through pipe 52. The treated kerosene, which is now substantially free from mercaptan components, is withdrawn from the coalescing section 12 through line 50 to storage.

From the above description it can be seen that the apparatus of the present invention is capable of performing a continuous process involving a multiplicity of steps. The use of the apparatus provides means for conducting sweetening operations in which much of the equipment formerly required to perform such operations may be eliminated.

It will be obvious to those skilled in the art that many modifications may be made within the scope of the present invention without departing from the spirit thereof, and the invention is to be restricted only in accordance with the appended claims.

I claim:

1. An apparatus for treating hydrocarbons comprising a vessel divided into an upper compartment, a central compartment and a lower compartment, said central compartment being divided into a first coalescing section, a second coalescing section and a washing section; means

for feeding liquid into said upper compartment; an outlet pipe having an opening near the top of and within said upper compartment connecting with said first coalescing section and means for transferring liquid from said first coalescing section successively through the lower compartment, the washing section, the second coalescing section and thence to storage.

2. An apparatus according to claim 1 in which the means for transferring liquid from the first coalescing section to the lower compartment includes a heater.

3. An apparatus according to claim 1 in which said lower compartment has a conically shaped bottom and the means for transferring liquid from the first coalescing section to the lower compartment includes means for simultaneously withdrawing liquid and chemicals from the conically shaped bottom of said lower compartment.

4. An apparatus for treating hydrocarbons comprising a vessel divided into an upper compartment, a central compartment and a lower compartment, said central compartment being divided into a first coalescing section, a second coalescing section and a washing section and said lower compartment having a conically shaped bottom; means for feeding liquid into said upper compartment; means for withdrawing liquid from the bottom of said upper compartment; an outlet pipe having an opening near the top of and within said upper compartment connecting with said first coalescing section; means for withdrawing liquid from near the bottom of said first coalescing section; means for transferring liquid from said first coalescing section to said lower compartment; means for feeding an oxygen-containing gas and treating chemicals to the liquid being transferred by said last named means; means for transferring liquid from an upper portion of said lower compartment to said washing section; an opening in the upper portion of said washing section leading into said second coalescing section; means for withdrawing liquid from near the bottom of said second coalescing section; and means for withdrawing liquid from the second coalescing section at a point above the last named means.

5. An apparatus according to claim 4 in which the means for transferring liquid from the first coalescing section to the lower compartment includes means for simultaneously withdrawing liquid and chemicals from the conically shaped bottom of said compartment.
